UNITED STATES PATENT OFFICE.

LEWIS Y. MYERS, OF CANTON, OHIO.

HAY-CARRIER TRACK.

SPECIFICATION forming part of Letters Patent No. 394,991, dated December 25, 1888.

Application filed December 29, 1887. Serial No. 259,302. (No model.)

To all whom it may concern:

Be it known that I, LEWIS Y. MYERS, a citizen of the United States, and a resident of Canton, county of Stark, State of Ohio, have 5 invented a new and useful Improvement in Tracks for Hay-Carriers, of which the following is a full, clear, and exact description, reference being had to the accompanying drawings, making part of this specification.

10 This invention relates to improvements in hay-carrier tracks, the object of which is to provide a strong and durable track that may be erected or removed without the service of a skilled mechanic and cost to the 15 farmer; that may be manufactured without the use of expensive machinery or labor, and at a greatly-reduced initial cost; and, further, it consists in the construction and combination of parts, as hereinafter described, and 20 set forth in the claims.

Figure 1 is an isometrical view of a hay-carrier track illustrating my invention. Fig. 2 is a cross-section through the coupling-clamp, as at Z, showing the parts in position; 25 Fig. 3, a cross-section through hanger-clamp, as at Y. Fig. 4 is an isometrical view comprising the ends of the track-bars and the coupler separated and enlarged.

Similar letters of reference indicate corresponding parts in all of the figures of the drawings.

A A represent the track-bars, which in this case consists of inverted-V or angle bars placed side by side, the outer edges, a and b, 35 turned downwardly and secured in parallel position, the edges a secured in the clamps B and C, as shown in Figs. 1 and 2. The end of the track-bars should be placed so as to break joints or overlap on the opposite bar, 40 as shown in Fig. 1. The inner edge or wing, a, of the bar is clasped and securely held by the clamps B and C. The said clamp B is composed of the parts D and E and the bolt F; the clamp C of the parts G and E and 45 the hanger J, the said hanger having a shoulder, K, and an annular screw-thread, L, on its lower portion, M, said thread adapted to a similar thread, N, in the lower portion, G, of the clamp C. The upper end of the 50 hanger J has a T-head, O, which is turned

crosswise of the track and passed through an oblong aperture, P, at the base of the hanger Q, which is secured to the rafters of the barn, and then turned to stand in line with the track, the ends of the T-head resting 55 on the bracket, as shown.

The outer edges, b, of the bars A are free and extend over the clamps. The bottom part, D, of the clamp B is provided with a centrally-located perforation for the bolt F, 60 and outwardly and upwardly projected wings h, having grooves R, the object of which is to provide room for the fin S, usually formed by the saw used in sizing the bars. This enlargement of the ends of the bars, when 65 clamped in the groove, secures the bars from end movement.

The upper part, E, of the clamp B has a central perforation for the bolt F, and the outer edges beveled to correspond with the 70 angle or face of the track-bar.

The hanger-clamps G are placed at such intervals as may be required to support the track and the clamp D where the track-bars are jointed, and at such other intervals as 75 may be required to secure the bars in their desired parallel position. The hanger-clamp is secured by the use of the threaded portion L of the hanger being turned into the threaded perforation of the clamping-plate G, and the 80 joint and intermediate clamps secured, as shown, by the bolts F.

If preferred, the point of the V-bar may be removed or rounded, as shown by the dotted lines at X, Fig. 2, forming an oval surface for 85 the tread of the carrier-wheel W, instead of the V, as shown in Fig. 1.

If desired, dowel-pins d may be used to prevent end movement of the track-bars, the pins resting in countersinks or perforations 90 d', as shown in Fig. 2.

Having thus fully described the nature and object of my invention, what I claim, and desire to secure by Letters Patent, is—

1. The combination, with the inverted angle-bars and clamps to secure the bars in fixed 95 relation to each other, of supporting-rods having a rotary engagement with the clamps and being formed T-shaped at their opposite ends, and supporting-brackets provided with sock- 100

- ets adapted to receive the T-heads when turned at an angle to their normal adjustment and lock the heads when the latter are turned into normal adjustment, substantially as set forth.
2. The combination, with the inverted angle-bars placed side by side with a space between them, of clamps constructed to embrace the inner wings of said bars, said clamps having outwardly and upwardly projected wings conforming to the incline of the angle-bars, a binding-cap, E, having beveled edges conforming to the inclination of the angle-bars, and a binding-bolt in engagement with the clamp and cap, substantially as set forth.
- 10
- 15

3. The herein-described means for securing the tracks, consisting, essentially, of the portion D, having outwardly and upwardly extending wings h, a binding-cap, E, provided with dowel-pins d, and a bolt for binding the parts E and D together, substantially as set forth.

In testimony whereof I have hereunto set my hand this 10th day of December, A. D. 25 1887.

LEWIS Y. MYERS.
